 Dickson Butane Equipment Co., San Mateo
 County, Calif., a corporation of California

Application January 17, 1940, Serial No. 314,243

21 Claims. (CL 48—180)

This invention relates to carburetors.

An object of this invention is to provide a carburetor wherein the gas is expanded to a predetermined pressure and is fed so as to maintain said predetermined pressure constant, and from which the expanded gas is discharged by a sensitive control responsive to the operation of the engine.

An object of this invention is to provide a carburetor in which the supply of fuel into the carburetor as well as the discharge of the fuel from the carburetor are positively controlled and regulated so as to maintain a predetermined supply through said carburetor.

Another object of this invention is to provide a carburetor wherein the fuel is expanded in the presence of heat so that a predetermined constant pressure is maintained for the supply of such expanded fuel to a usual mixing chamber or the like.

Another object of this invention is to provide a carburetor wherein the fuel is expanded in the presence of heat in an expansion chamber and the fuel intake is regulated by a mechanism controlled by the expanded pressure of the fuel, and the discharge from which expansion chamber is controlled by the suction of the engine.

Another object of this invention is to provide a novel and efficient expansion device for carburetors, and particularly to provide a highly efficient heat exchanger for carburetors in which the fuel is contacted with a large heating surface within a comparatively limited space of an expansion chamber.

Another object of this invention is to provide a novel mechanism for controlling the feed of the fuel to the carburetor so as to maintain a predetermined gas pressure in the carburetor.

Another object of this invention is to provide a positive fuel discharge mechanism for carburetors which is sensitively controlled by suction from the engine and which provides for idling discharge as well as for positive shutting off of the gas flow from the carburetor when for any reason the engine is stopped or the control is out of order.

Another object of this invention is to provide a method of carburetion for gas wherein the gas is expanded to a predetermined pressure in the presence of heat, the gas being introduced to and withdrawn from said heat exchange at the hottest point of the carburetor, and wherein the introduction of the gas into the carburetor is controlled by the expanded pressure within the carburetor so as to maintain a constant pressure,

and the discharge from the carburetor is regulated by suction from an engine to which said carburetor is connected, said discharge regulation being in two steps, namely by the steps of opening to a predetermined idling discharge by the action of the higher vacuum of the manifold of the engine, and then regulating the opening by the vacuum at the mixing chamber.

Another object of this invention is to provide a carburetor for fuel, such as butane, liquefied petroleum gas, natural gas, or other gases of comparatively low boiling point, wherein the fuel is pre-expanded to a predetermined pressure, and fed to the engine through devices positively controlled by the engine so as to tightly shut off the feed when the engine is inoperative but to be sensitive to the slightest idling operation of the engine to feed the fuel.

Another object of the invention is to provide a diaphragm actuator for the flow of expanded fuel from a carburetor which positively opens the fuel discharge valve by a balanced control responsive to the slightest suction caused by an idling engine, and which is fully responsive to the action of engine suction exerted through a second diaphragm so that said control automatically closes the discharge valve and prevents the discharge of fuel when the suction at the diaphragm is broken for any reason.

Another object of this invention is to provide a carburetor in which highly volatile fuel or fuel of low boiling point and the like is fed to the carburetor under high pressure, is expanded and reduced to a predetermined lower pressure in said carburetor and is completely confined in said carburetor and positively held against escapement by said predetermined pressure and by sensitive balanced discharge mechanisms actuated by engine suction for controlling the discharge.

Other objects of this invention are to provide a carburetor method and device that will be superior in point of simplicity, safety, inexpensiveness of construction, positiveness of operation, facility and convenience in use and general efficiency.

Other objects of the invention together with the foregoing will be set forth in the following description of the preferred method and the preferred embodiment of means for practicing the same, which is illustrated in the drawings accompanying and forming part of the specification. It is to be understood that I do not limit myself to the embodiment disclosed in said description and the drawings as I may adopt varia-

tions of my preferred forms within the scope of my invention.

With the foregoing and other objects in view, which will be made manifest in the following detailed description, reference is had to the accompanying drawings for the illustrative embodiment of the invention, wherein:

Fig. 1 is a front view of the carburetor.

Fig. 2 is a sectional view of the carburetor, the section being taken on the line 2—2 of Fig. 1, 10 also showing diagrammatically the connection to the mixer.

Fig. 3 is a sectional view of the carburetor so as to show the heat exchanger in its expansion chamber.

Fig. 4 is a front view of the carburetor partly broken away to show the shut-off diaphragm control, and the intake control chamber.

Fig. 5 is a sectional view of the carburetor, showing the intake control and expansion control regulator, the section being taken on the lines 5—5 of Fig. 4.

Fig. 6 is a fragmental sectional view of the discharge regulator in fully opened position.

Fig. 7 is a fragmental sectional view of the 25 discharge regulator in fully closed or shut-off position;

Fig. 8 is a sectional view of the discharge regulator in idling position, and

Fig. 9 is a fragmental, sectional detail view, 30 showing the relative arrangement of the spray orifices on the nozzle tube of the heat exchanger device.

In general the method of carburetion in accordance with my invention includes the steps of 35 expanding the fuel in the presence of heat, maintaining a predetermined constant pressure of the expanded fuel by controlling the fuel intake by the expanded pressure so as to keep the fuel intake closed until the expanded pressure falls below a predetermined pressure, and regulating the discharge of the expanded fuel from the carburetor by the suction of the engine on which the carburetor is used.

The first step, namely the expanding of the 40 fuel, is accomplished by spraying the fuel over a heating element which is so divided as to provide a large exposed surface and by confining the first or primary fluid flow in the carburetor to a path along said heating surface so as to compel the fuel to impinge upon the heating surface at many points. In addition the fuel is so circulated that the fuel under pressure is introduced into the carburetor at about the place where the heating medium for the heating element enters and is the hottest. The expanded fuel is also returned through a secondary path to about said hottest portion of the carburetor when the expanded gas is passed toward the discharge orifice of the carburetor.

The second step, namely the maintaining of a 45 constant predetermined expanded pressure, is accomplished by the provision of an intake control mechanism which closes the fuel intake of the carburetor by the direct application of the expanded pressure against a predetermined yieldable opening force so as to keep the intake closed at all times while the expanded pressure is sufficient to overcome said yieldable opening force. When the expanded pressure becomes 50 lower than the yieldable opening force then the latter acts to open the intake and admit additional fuel to be expanded until the pressure is again built up to close the intake. This step maintains a substantially constant pressure and

also acts as a safety measure in preventing the building up of dangerous pressure in the expansion chamber of the carburetor.

5 The third step, namely the discharge regulation according to engine suction, is accomplished in two steps. First the discharge of the expanded fuel from the carburetor is entirely and automatically shut off whenever the engine suction does not operate the discharge regulating mechanism. Upon the starting of the engine and while it is idling the discharge mechanism is unlocked and kept opened to a preset opening by the action of the manifold suction of the engine. Secondly the released discharge mechanism is then regulated by the action of the suction at the mixing chamber of the carburetor leading to said engine. This permits a positive opening for idling of the engine, a flexible control through the usual throttle valve, and the automatic shutting off of the fuel discharge whenever the discharge regulator is not responsive to engine suction.

In the herein illustration is shown an embodiment of my invention in a type of carburetor particularly adapted for use in connection with gases of low boiling point. For instance butane gas is provided in liquid form in pressure tanks and it must be expanded to a suitable lower pressure, such as to about ten pounds pressure, in order to be used in gas form. The various novel features of my device are capable of different uses in the regulation of fuel feed for combustion.

In the herein embodiment of my device in general I make use of an expanding device A, an intake control mechanism B and a discharge regulating device C.

The expanding device A includes a heat exchanger 11 and a multiple spray or nozzle tube 12 above the heat exchanger 11, both disposed in an expansion chamber 13 and both being covered by a shield 14. The expansion chamber 13 is comparatively flat and extends over the base 16 of the casing 17 on which latter all the herein devices and mechanisms are supported.

The heat exchanger 11 is formed into a coil-like conduit through which a heating medium, such as hot water, is passed. The heat exchanger 11 is made of a plurality of parallel tubes 18 the ends of which are mounted in head boxes 19 and 21. Each head box is divided by transverse partitions 22 into separate head spaces each of which communicates the adjacent ends of two of the tubes 18. The series of partitions 22 of the opposite head boxes 19 and 21 are so staggered relatively to each other that the respective opposite heads overlap and connect the tubes 18 into one continuous conduit with tubes 18 forming turns of the conduit consecutively in opposite directions. An inlet 23 is detachably connected into the end of the first or top turn of the heat exchanger 11 and an outlet 24 is detachably connected to the lower end turn of said heat exchanger 11. It is to be noted that the connections 23 and 24 are insertable from the outside of the expansion chamber 13. The heat exchanger 11 is firmly held in the chamber 13 by set screws 26 extended from the outside of the chamber 13 into engagement with the head box 21 so as to coat with securing nuts 27 of the intake 23 and of the outlet 24 for holding the heat exchanger 11 in place. The bottom of the expansion chamber 13 is covered by a removable cover 28 so that the heat exchanger 11 and parts of the heat exchanger device may be

removed from the expansion chamber 13. The heating medium, such as hot water, circulates from the inlet 23 through the turns formed by the tubes 18 and the partitioned head boxes 19 and 21 to and out through the outlet 24, thereby exposing a large heating surface in the comparatively small chamber 13.

The nozzle tube 12 is made of a perforated tube insertable through a hole 29 in the side wall of the chamber 13 and seated in a socket 31 opposite said hole 29. The outer end 32 of the nozzle tube 12 is closed and it is threaded or otherwise adapted to be secured in place. The nozzle tube 12 is extended parallel with and above the first turn or top tube 18 of the heat exchanger 11 and has a series of nozzles or jets 33 which gradually increase in size toward the closed end 32 so that the fuel is introduced in substantially equalized sprays over the top of the heat exchanger 11. The fuel is fed into the open end of the nozzle tube 12 from the socket 31 and from an intake passage 34. It is to be noted that the intake passage 34 and the open end of the nozzle tube 12 are adjacent to the inlet 23 of the heat exchanger 11 which is the warmest part of the expansion chamber 13. In this manner the fuel is heated in its passage to the nozzles and the subsequent heat exchange is rendered still more efficient.

The shield 14 is closed at its top and sides and extends over the nozzle tube 12 and over the heat exchanger 11 so as to leave a space 36 between each of its sides and the adjacent wall of the chamber 13. The shield 14 is open at its bottom end 37. This arrangement of the shield 14 confines the path of the fuel from the nozzles 33 to the surfaces of the heat exchanger 11 and thereby causes the fuel spray to impinge upon the many exposed heating surfaces of the heat exchanger and be expanded before it leaves the primary path of the fuel within the shield 14. The fuel thus expanded is forced then to continue on a secondary heat exchanger path namely through the spaces 36 between the sides of the shield 14 and the walls of the expansion chamber 13 upwardly to the hotter upper part of said chamber 13, and during this secondary path the gas or vapor contacts the warmed walls of the shield 14.

The intake control mechanism B is located in a separate valve chamber 38 formed integral with the casing 17 and is offset as shown in Fig. 5 so as to be adjacent and partly in extension of the wall 39 containing the intake passage 34. The wall 39 is the heated wall and it extends to form a part of the wall of the valve chamber 38. In the extension of the wall 39 is secured from the outside an intake connection 41 from a usual fuel tank. A protruding intake part 42 on the end of the connection 41 is located at an angle to the intake passage 34 so as to feed the fuel into said intake passage 34 when the intake port 42 is uncovered. A hole 43 extends through the extension of the wall 39 in continuation of the connection 41 and into the valve chamber 38. Into this hole 43 slidably fits a valve rod 44 which extends across the valve chamber 38 in an inclined position in axial alignment with the intake port 42. The tail end of the valve rod 44 is guided in a socket 46 in the wall 47 of the valve chamber 38. The valve end of the valve rod 44 is recessed and in the recess thereof is secured a compressible valve seat fitting over the protruding orifice of the intake port 42.

The intake valve rod 44 is reciprocated by a diaphragm 48 held by a cover 49 across the top of the valve chamber 38. A bell crank 51 is pivoted at one end to a lug 52 on the underside of the diaphragm 48 and at its corner to a stay 53 fixed in the wall 47. The position of the bell crank 51 is such that its free end 54 fits into a suitable slot in the valve rod 44 and moves the valve rod 44 toward the intake port 42 when the diaphragm 48 is urged outwardly of the valve chamber 38, and is moved away from the valve port 42 when the diaphragm 48 is moved inwardly of the valve chamber 38. A spring 56 in the cover 49 normally forces the diaphragm 48 inwardly of the valve chamber 38 so as to urge the valve rod 44 into valve opening position. This spring 56 is of a predetermined tension so as to overcome a definite pressure in the valve chamber 38. The spring is such that it will be held compressed, and the diaphragm thus held in the valve closing position, by the constant pressure to which the fuel is to be expanded in the heat exchanger device A. Whenever the expanded gas pressure falls below said desired pressure the spring will move the diaphragm 48 inwardly of the valve chamber 38 and move the valve rod 44 so as to uncover the intake port 42. Thus the fuel under pressure will be introduced into the intake passage 34 and into the heat exchanger device A as heretofore described. When sufficient fuel is expanded to create the desired pressure then the diaphragm is moved outwardly of the valve chamber 38 against the action of the spring 56 and the intake port 42 is again closed. The valve chamber 38 partly overlaps the front wall of the expansion chamber 13 near the top and a hole 57 through said wall, as shown in Fig. 4, transmits expanded gas from the top of the expansion chamber 13 into the valve chamber 38 so that the diaphragm 48 is actuated by the pressure of the gas expanded by the heat exchanger device A.

The discharge regulating device C includes a diaphragm actuated valve mechanism. On the front part of the top of the expansion chamber 13 is a separate discharge valve chamber 58 which receives the expanded gas through a discharge passage 59 shown in Fig. 2. The discharge valve chamber 58 has vertically aligned threaded openings 61 and 62 into which is threadedly secured a valve cage 63 held in place by an outside locknut 64. The valve cage 63 has apertures 66 around a portion of its side walls through which the expanded gas passes from the discharge valve chamber 58 to the interior of the valve cage 63. On the end of the valve cage 63 in the inner opening 61 is an outwardly extended sharp rim forming a discharge orifice or discharge port 67 which communicates with the apertures 66 through the inner cavity 68 of the valve cage 63. The valve cage 63 is hollow throughout its entire length.

A valve 69 is opposite the discharge port 67 and has in it recessed a compressible seat 71 for sealing engagement with the mouth of the discharge port 67. From one side of the valve 69 extends a spring cup 72 which also serves as an alignment guide in a spring socket 73 formed in the front of the casing 17. A spring 74 in the spring socket urges the valve toward the discharge port 67. Into the other face of the valve 69 is threaded a valve stem 76, a flange of which holds the compressible seat 71 in place. This valve stem 76 extends axially into the cavity 68 of the valve cage 63. Above the valve cage cavity 68 the pas-

sage through the valve cage 63 is narrower and it guides another spring cup 71 from which extends an extension stem 78. In the second spring cup 71 and around the extension stem 78 is another spring 79 which as its other end bears against a bushing 81 adjustably threaded into the outer end of the valve cage 63. The relative forces exerted by the springs 74 and 79 are such that the inner spring 74 is capable to move the valve 71 into closed position, seat it over the discharge port 67 and hold the valve in closed position in such a manner that in said closed position the closing spring 74 is substantially balanced by the outer spring 79 and by the normal expanded gas pressure issuing from the heat exchanger device A. To achieve such substantial balance the tension of the outer spring 79 may be adjusted by the bushing 81.

For the idling of the engine, when the suction in the usual mixing chamber is not sufficient to open the valve, a positive valve opening device is provided at the outer end of the valve cage 63. A screw plug 82 is adjustably threaded into the bushing 81. The screw plug is hollow and has therein a slideable plunger 83. A reduced plunger abutment 84 protrudes from the plunger 83 through a small hole 85 in the bottom of the plug 82. A spring 87 in the screw plug 82 urges the plunger 83 toward the end of the extension stem 78 of the valve 69. The length of the extension stem 78 is such that in the closed position of the valve 69 it pushes up the plunger abutment 84. In this manner the force of the plunger spring 87 is transmitted to the extension valve stem 78 so as to offset the force of the closing spring 74 to an adjusted degree and keep the valve slightly open for idling. The extent of valve opening for idling can be adjusted by adjusting the position of the screw plug 82 in the bushing 81 and in the valve cage 63. The outer end of the valve cage 63 has a cap 88 threaded thereon to protect these valve adjustments.

The discharge valve 69 is regulated and controlled by diaphragms actuated by the suction of the engine on which the carburetors are used. A discharge regulating diaphragm 89 is mounted in a diaphragm control chamber 91, the bottom 92 of which latter is the front wall of the expansion chamber 13. The discharge regulating diaphragm 89 is held in place on a ledge 93 by a securing and spacing ring 94. An air vent 95 between the wall 92 and the diaphragm 89 releases back pressure and assures free action of the diaphragm 89. A lever 96 is pivoted at one end thereof to a lug 97 of said diaphragm 89. The lever 96 is extended through a large opening 98, in the ring and in the side of the chamber adjacent the discharge valve 69 and has its outer end bent and forked so as to form a yoke 99 fitting over a neck groove 101 at the base of the valve 69. The lever 96 is fulcrumed at 102 on ears 103 near its bend or corner so that when the discharge regulating diaphragm 89 is moved toward the lever 96 then the latter moves the valve 69 away from the discharge port 67 and when said diaphragm 89 is not subjected to suction then the outer or closing spring 74, is permitted to move the valve 69 back toward the discharge port 67.

The suction for the operation of the discharge regulating diaphragm 89 is created at the usual mixing chamber 104 of a usual carburetor, the fuel line 106 of which is connected through a replaceable Venturi outlet 107 to an outlet space 108 into which the fuel is discharged from the discharge port 67. The opening 98 also opens

5 into said outlet space 108 so that the mixing suction is also exerted on the diaphragm 89. This suction depends on the degree of opening of the throttle valve 109 but it is lower than the manifold suction between the throttle valve 109 and the engine. Thus the discharge of the expanded gas to and through the mixing chamber 104 is regulated and controlled in a manner quickly responsive to the throttle valve adjustments.

10 When the engine stops entirely then the aforesaid idling opening must be closed by an automatic shut-off mechanism. For this purpose a so-called locking diaphragm 111 is disposed in the diaphragm control chamber 91 and is held in 15 parallel spaced relation to the regulating diaphragm 89 between a front cover 112 and the top of the spacing ring 94. The locking diaphragm 111 separates the chamber under the dished cover 112. A locking abutment 113 on the locking diaphragm 111 abuts against the lug 97 on the regulating diaphragm. A spring 114 in the center 20 of the cover 112 bears against the center of the locking diaphragm 111 so as to urge the locking abutment 113 against the lug 97 and against the end of the lever 96 so as to positively force the discharge valve 69 into closed position and firmly lock it against opening. The space in the dished cover 112 is connected by a conduit 116 to the engine at a point past the throttle valve 109 so as 25 to subject the outside face of the locking diaphragm 111 substantially to the manifold suction. The manifold suction is much higher and exerts more suction force than the suction in the mixing chamber 104. Therefore as soon as the engine is started, the manifold suction quickly 30 pulls the locking diaphragm 111 out of locking position, and holds this locking diaphragm 111 in inoperative position as long as the engine is in 35 operation. This permits the opening of the discharge valve 69 for idling and its regulation thereafter through the lever 96 and the regulating diaphragm 89 and by the suction in the mixing chamber 104 of the carburetor. If the engine stops, or the locking diaphragm 111 for some 40 reason is out of order and does not react to suction, the spring 114 automatically shuts off the gas supply and positively prevents the flooding of 45 the carburetor.

50 When the gas is shut-off at the discharge port 67, the pressure in the expanding mechanism shuts-off the intake also and prevents excessive pressure in the device.

55 The device is simple and unitary in character. The expansion chamber 13 functions as a base which is covered at its front by the diaphragm control chamber 91, and carries at its top, or at its heated end both the intake control chamber 38, and the separate discharge chamber 58, with an outlet 107 in front of the discharge chamber 58. The mixing chamber may be directly mounted on the outlet 107 or the device may be connected by the flexible line 106 to a usual carburetor mixing chamber 104.

60 It is to be understood that while the features in the herein illustrative embodiment are described as parts of a carburetor, certain of the novel features herein may be used on fuel vaporizers or fuel expander devices for different purposes so as to render the combustion of gases and fuels more efficient, safe and economical.

65 Having thus described my invention, what I now claim and desire to secure by Letters Patent is:

70 1. In a carburetor the combination with a chamber through which the fuel is passed in said

carburetor; of a heat exchanger in said chamber comprising, a conduit extended through said chamber and carrying a heating medium, means to introduce said fuel into the chamber and over said conduit, and a shield spaced from the chamber walls and extended over the said fuel introducing means and over said conduit so as to confine a primary fuel path around the surface of said conduit, and a secondary path for the expanded fuel in the space between the shield and the chamber walls.

2. In a carburetor the combination with a chamber through which the fuel is passed in said carburetor; of a heat exchanger in said chamber comprising, a conduit formed substantially in the shape of a coil and containing a heating medium, a spray conduit extended along said conduit for introducing a fuel, a shield fitting over said spray conduit and said coil to direct the primary passage of the fuel over the turns of said coil, said shield being open adjacent the last turn of the coil, and being spaced from the wall of said chamber so as to provide a secondary passage for the fuel, an outlet from said expansion chamber outside of the closed end of the shield, and means adjacent said outlet to control the intake of the fuel into said spray conduit.

3. A heat exchanger for fuel gas, comprising an expansion chamber, an intake nozzle to conduct the fuel gas into said chamber, means extended over said nozzle in spaced relation to the walls of the chamber so as to divide the chamber into a primary path and a secondary path wherein the gases pass successively in opposite directions the primary path leading away from said nozzles, and a heating element with a tortuous heating surface positioned in the primary path of the fuel.

4. In a carburetor, the combination with a heat exchanger for expanding the fuel and means to introduce the fuel to the heat exchanger; of an adjustable intake mechanism, between the fuel introducing means and the fuel supply, means acted upon by a predetermined expanded fuel pressure from said heat exchanger to keep said intake mechanism closed, and means operating only at expanded pressures lower than said predetermined pressure so as to open said intake mechanism.

5. A control mechanism for fuel intake comprising, an intake port, a valve to cover the intake port, a pressure chamber adapted to receive fuel under pressure, means in said pressure chamber to normally urge the valve into intake opening position, means actuated by the pressure in said chamber to hold said urging means in valve closing position whenever the pressure in said chamber is at or above a predetermined pressure and to release said opening at other times, and means to introduce expanded fuel under pressure into said pressure chamber independently of the intake valve for controlling the intake valve position.

6. An intake control for a carburetor having an expanding means for the fuel, of a separate control chamber, an intake port outside said chamber leading to said expanding means, a valve slidably extended through a wall of the chamber to cover said port, a diaphragm in said chamber being actuated by the pressure in said chamber, means of connection between the diaphragm and the valve to close said valve when the diaphragm is held under predetermined pressure in the chamber and to open said valve when the pressure in said chamber is reduced below

said predetermined pressure, and means to conduct expanded fuel from said expanding means into said chamber.

5 7. In a carburetor, an expansion chamber, a heat exchanger mechanism in said chamber, means to introduce the fuel to said heat exchanger means, a pressure regulator chamber communicating with the expansion chamber so as to have equalized pressure in both chambers, a pressure actuated mechanism in said pressure regulator chamber, a closure element connected to said pressure actuated mechanism and extended through the wall of said pressure regulator chamber to the intake of said fuel introducing means so as to close and open said intake in accordance with the positions of said pressure actuated mechanism, said pressure actuated mechanism being adjustable to be held in intake closing position by a predetermined pressure in said chamber, and means to move said pressure actuated mechanism to intake closing position when the pressure in said regulator chamber is below said predetermined pressure.

25 8. In a carburetor, the combination with the expansion chamber of the carburetor and the means to convey the fuel to the expansion chamber, of a separate chamber containing the same pressure as that of the expanded gases in the expansion chamber, an intake in a wall and outside of the separate chamber leading to said fuel conveying means, a slideable valve member in the separate chamber extended into the wall of the separate chamber to cover said intake, a diaphragm in the separate chamber, means to urge the diaphragm into the space of the separate chamber by a predetermined force, said diaphragm being so located in said separate chamber that the gas pressure in said separate chamber counteracts said urging means at said predetermined pressure, and means of connection between said valve member and said diaphragm to hold said valve member in intake closing position when the pressure in said separate chamber is sufficient to resist said urging means.

40 9. In a pressure regulator for carburetors, a fuel expansion means for the carburetor, a separate fuel intake regulator chamber, a fuel passage leading in a wall and outside of said regulator chamber into said expansion means, a valve member slidably guided within said chamber and into said wall so as to obstruct said fuel passage in closed position, a diaphragm in said regulator chamber, resilient means to hold said diaphragm at a predetermined tension against the pressure in said chamber, a connection between said diaphragm and said valve member to hold the valve member in passage obstructing position until the pressure in said regulator chamber is insufficient to counteract the predetermined tension of said resilient means.

55 10. A discharge mechanism for a gas carburetor, comprising a discharge orifice, a valve for covering said orifice, resilient means to hold said valve seated on the orifice in a substantially balanced closing position, resilient means to unbalance said first resilient means so as to keep the valve open to a predetermined discharge opening, and means to automatically seat said valve against the action of said second resilient means when the engine is not running.

70 11. A discharge mechanism for a carburetor, comprising a discharge orifice, a valve adapted to be seated on said orifice, a diaphragm actuated lever to regulate the moving of said valve away from the orifice, means to connect said dia-

phragm to the suction action of the carburetor mixing chamber, means to force the lever into valve closing position, and a second diaphragm actuated by the manifold suction of the engine to relieve the valve closing action of said forcing means from said lever when the engine is running.

12. A discharge mechanism for carburetors, comprising a discharge orifice, a valve for the discharge orifice, a diaphragm actuated by the suction of the carburetor mixing chamber, means of connection between the valve and the diaphragm for opening said valve in accordance with the suction in said mixing chamber, means to hold the diaphragm and said means of connection in valve closing position, and suction actuated means to release said holding means when the engine is in operation.

13. In a carburetor, a fuel discharge orifice, a valve to cover said orifice, and means to control said valve comprising, a pair of spaced diaphragms, the space between the diaphragms communicating with the suction of the mixing chamber of the carburetor, the first diaphragm being adapted to be actuated by the suction in the mixing chamber, means of connection between said first diaphragm and the valve for opening the valve by said suction, the second diaphragm being connected to the manifold suction of the engine so as to be actuated thereby, means to normally force the first diaphragm into valve closing position, and means of connection between said forcing means and the second diaphragm to release said forcing means from the first diaphragm when the second diaphragm reacts to a manifold suction.

14. In a carburetor, means to discharge fuel to the mixing chamber of the carburetor, a valve to control the fuel discharge, and a valve control mechanism comprising, a pair of spaced diaphragms, the space between the diaphragms communicating with the suction in the mixing chamber, means connecting one of said diaphragms to said valve so as to open the valve when the diaphragm is subjected to said mixing chamber suction, yieldable means exerting on the first diaphragm a locking force greater than and opposite to the force of the suction on said first diaphragm so as to hold the first diaphragm in valve closing position, the second diaphragm being so related to said yieldable means as to overcome its locking force when subjected to suction, and means to subject said second diaphragm to manifold suction of the engine so as to release the force of said yieldable means from said first diaphragm.

15. A valve control for fuel discharge mechanism of carburetor, comprising, a pair of spaced diaphragms in the same chamber, the space between the diaphragms communicating with the discharge suction of the carburetor mixing chamber, a lever extended from said space to connect one of the diaphragms to the discharge mechanism so as to control the discharge from said discharge mechanism, means exerting a yieldable force on said diaphragms so as to hold said first diaphragm and said lever in a discharge closing position, and means to conduct the force of the manifold suction to the outside of the second diaphragm so as to release said yieldable force from the first diaphragm and allow opening of the discharge mechanism.

16. A discharge mechanism for carburetors comprising a casing secured in the discharge chamber, a discharge orifice on said casing, a

5 valve for engagement with said orifice, means to support the valve in a substantially balanced closed position, a valve stem extended from said valve axially into said casing, an abutment holder adjustably secured into said casing, an abutment slidably held in said holder so as to abut said valve stem, and resiliently yieldable means to urge said abutment against the stem so as to offset the balance of said valve supporting means and hold the valve open to an opening determined by the position of said abutment.

17. A discharge mechanism for carburetors comprising a casing secured in the discharge chamber, a discharge orifice on said casing, a valve for engagement with said orifice, means to support the valve in a substantially balanced closed position, a valve stem extended from said valve axially into said casing, an abutment holder adjustably secured into said casing, an abutment slidably held in said holder so as to abut said valve stem, and resiliently yieldable means to urge said abutment against the stem so as to offset the balance of said valve supporting means and hold the valve open to an opening determined by the position of said abutment, and means automatically to close said valve against the action of said abutment when the engine is not running.

18. A discharge mechanism for carburetors comprising a casing secured in the discharge chamber, a discharge orifice on said casing, a valve for engagement with said orifice, means to support the valve stem extended from said valve axially into said casing, an abutment holder adjustably secured into said casing, an abutment slidably held in said holder so as to abut said valve stem, resiliently yieldable means to urge said abutment against the stem so as to offset the balance of said valve supporting means and hold the valve open to an opening determined by the position of said abutment, and means releasable by the manifold suction of the engine to hold said valve in closed position against the action of said abutment.

19. A carburetor comprising an expansion 45 chamber, an intake regulating chamber, a discharge regulating chamber, said expansion chamber and said intake regulating chambers communicating with each other so as to contain substantially equalized pressure, the pressure in said discharge regulating chamber being controlled by the suction at the fuel discharge orifice of the carburetor; a diaphragm actuated fuel intake control mechanism in said intake regulating chamber including a diaphragm responsive to the pressure in said intake regulating chamber, and an element extending to the outside of said intake regulating chamber to control the fuel intake of said expansion chamber; and a discharge control mechanism including a diaphragm in said discharge control chamber to operate said discharge control mechanism in accordance with the suction at the discharge orifice.

20. A carburetor comprising an expansion chamber, an intake regulating chamber, a discharge regulating chamber, said expansion chamber and said intake regulating chamber communicating with each other so as to contain substantially equalized pressure, the pressure in said discharge regulating chamber being controlled by the suction at the fuel discharge orifice of the carburetor; a diaphragm actuated fuel intake control mechanism in said intake regulating chamber including a diaphragm responsive to the pressure in said intake regulating chamber, and an element extending to the outside of

said intake regulating chamber to control the fuel intake of said expansion chamber, a discharge control mechanism including a diaphragm in said discharge control chamber to operate said discharge control mechanism in accordance with the suction at the discharge orifice, releasable means to lock said discharge control mechanism in a position to close the discharge orifice, and a second diaphragm in the discharge control chamber acted upon by the manifold suction of the engine so as to release said locking means.

21. A carburetor comprising, an expansion chamber, an intake regulating chamber, a discharge regulating chamber, said expansion chamber and said intake regulating chamber communicating with each other so as to contain substantially equalized pressure, the pressure in said discharge regulating chamber being controlled by the suction at the fuel discharge orifice of the carburetor; a diaphragm actuated fuel intake control mechanism in said intake regu-

lating chamber including a diaphragm responsive to the pressure in said intake regulating chamber, and an element extending to the outside of said intake regulating chamber to control the fuel intake of said expansion chamber; a discharge control mechanism including a diaphragm in said discharge control chamber to operate said discharge control mechanism in accordance with the suction at the discharge orifice, releasable means to lock said discharge control mechanism in a position to close the discharge orifice, a second diaphragm in the discharge control chamber acted upon by the manifold suction of the engine so as to release said locking means, a heat exchange member in said expansion chamber, an inlet for the heating medium for said heat exchange member being adjacent to the intake regulating chamber and to the fuel intake of the expansion chamber.
